DRAFT REGULATING APPARATUS

Richard A. Walker, St. Joseph, Mo.

Application February 6, 1939, Serial No. 254,817

5 Claims. (Cl. 236—45)

My invention relates to improvements in draft regulating apparatus particularly adapted for regulating the draft in smoke pipes of stoves, furnaces and the like.

One of the objects of my invention is the provision of a novel draft apparatus of the kind described which is particularly adapted for use with flues of strong draft pressure, and having novel means for manually regulating the draft to suit different temperatures and different stoves or furnaces; and having novel means for indicating the draft pressure in the smoke pipe at the time; and provided with novel means by which the desired draft will be automatically retained, after the manual adjustment, regardless of the draft fluctuations due to atmospheric or other conditions.

A further object of my invention is the provision of a novel draft regulating apparatus which is, simple, cheaply made and easily and quickly installed in operative condition, which can be easily and quickly adjusted to suit different positions of the smoke pipe where the apparatus is installed, which is strong, durable, not likely to get out of order, and which is efficient in operation.

The novel features of my invention are hereinafter fully described and claimed.

In the accompanying drawings, which illustrate the preferred embodiment of my invention:

Fig. 1 is a vertical sectional view, showing the pipe vertically disposed and the indicating pointer registering with the "Med." draft designation on the dial, the damper being shown partly closed.

Fig. 2 is a top view, showing the pipe vertical and the damper fully open.

Fig. 3 is an enlarged vertical fragmental sectional view, showing the pipe vertical and the pointer indicating "low" on the dial.

Fig. 4 is a side view, showing the pipe horizontally disposed and the vane closed or in the "low" position.

Fig. 5 is a side elevation, showing the pipe vertical, and the vane in the "high" draft position.

Fig. 6 is a vertical sectional view of what is shown in Fig. 5.

Fig. 7 is a side elevation, showing the pipe inclined, and the vane in the closed or "low" position.

Fig. 8 is an enlarged side elevation of the dial.

Fig. 9 is an enlarged top view of the dial.

Similar characters of reference designate similar parts in the different views.

1 designates the body of a T pipe joint, and 2 the lateral pipe section or tubular arm, the opening therethrough communicating, as usual with the interior of the body 1 and with the outside atmosphere.

In the body 1 is pivoted the usual damper 3, disposed between the discharge end of said body and the arm 2, as shown in Figs. 1, 4 and 7.

In the outer end of the arm 2 is circumferentially fitted a vane support comprising a ring 4, which is held in its adjusted position by a clamping screw 5 provided with a nut 6 and extending through two ears 7 provided at the outer end of the arm 2. By turning the screw 5, the ring 4 may be clamped tightly after its adjustment.

In the arm 2 is disposed a vane or damper 8 having for its axis two aligned pins 9 disposed above the horizontal plane of the center of the vane 8 and respectively pivoted in two eyes 10 provided on the ring 4 adjacent to opposite edges of the vane.

The vane 8 above its axis has a transverse threaded hole in which is fitted a screw 12 having on it a tightly fitted nut 11 and a head 12, the nut, head and screw comprising a weight which is adjustable transversely to the axis of the vane 8, whereby the weight may be adjusted inwardly or outwardly so as to require different draft pressures for swinging the lower edge of the vane inwardly from the closed position, shown in Figs. 3, 4 and 7.

Circumferentially adjustable around the opening through the arm 2 is a pressure draft designating means comprising a dial plate 13 disposed edge up, and preferably fastened at its outer end to the bottom and inner side of the ring 4, so as to be circumferentially adjustable with the ring 4.

Opposite sides of the dial plate 13, which extends inwardly from the ring 4, are inscribed with the pressure designating symbols "low," "Med." and "high" arranged in an arcuate row in the order named, "low" being adjacent to the ring 4.

For indicating on the dial plate 13 the draft pressure in the pipe at the time, means actuated by the vane 8 are provided, which as shown, comprises a pointer 14 attached to the vane 8 at the periphery thereof and which, registers with the inscriptions on the dial, as the vane swings inwardly and outwardly. A lateral projection 15 on the dial plate 13 limits the outward swinging of the lower edge of the vane to the closed position shown in Fig. 3. A lateral projection 16 on

the inner end of the dial plate 13 limits the inward swinging of the lower edge of the vane 8.

In the operation of adjusting the apparatus, the T joint is inserted in the smoke pipe with which it is to be used, the ring 4 being then adjusted in the arm 2 to a position in which the axis of the vane 8 will be horizontal, irrespective as to whether the body 1 is vertical, as shown in Figs. 1, 3, 5 and 6; or horizontal, as shown in Fig. 4; or inclined, as shown in Fig. 7.

The damper 3 is turned to the open position shown in Fig. 2. The screw weight 12 is then adjusted in the vane 8 to a predetermined position, which is arbitrarily determined, to suit the particular type of furnace with which the apparatus is to be associated with, and to the particular draft required for such furnace. The adjustment of the weight 12 determines the draft pressure required to swing the lower edge of the vane inwardly from the closed position.

The damper 3 is then adjusted to suit the strength of draft pressure required at the time in the furnace. If the day is mild, the damper 3 is turned to near the closed position, upon which the draft in the body 1 and, consequently, in the arm 2, will be so restricted that the vane 8 will swing to near the position shown in Fig. 3, and the pointer will indicate "low."

If the atmospheric outside temperature is colder, and more furnace draft is desired, the damper 3 is turned so that the pointer 14 will indicate "Med." on the dial 13, as is shown in Fig. 1.

If the outside temperature is very cold, and a high draft is required in the furnace, the damper 3 is turned to nearer the open position, as shown in Fig. 6, upon which the vane 8 will swing to the position shown in Fig. 6, and the pointer 14 will indicate "high" on the dial.

The pointer 14 and the dial 13 serve to guide the operator in adjusting the damper 3, to suit the furnace draft desired at the particular time. After such adjustment has been made, the vane 8 will automatically swing to retain the desired draft regardless of fluctuations of draft pressure in the flue.

Many modifications of my invention, within the scope of the appended claims, may be made without departing from the spirit of my invention.

What I claim is:

1. In a draft-regulating apparatus, in combination, a T joint having a tubular body, adapted for insertion into a smoke pipe as a part thereof, and a lateral pipe section the opening therethrough communicating with the interior of the body and the outside air, a manually adjustable damper in said body between the discharge end thereof and said lateral pipe section, a vane in said opening operable by differences in pressure at opposite sides thereof, and supporting means for said vane adjustable circumferentially in the plane of the axis of the vane, of means adjustable with said supporting means for designating different draft pressures, and means actuated by said vane for indicating on said pressure designating means the draft pressure in said smoke pipe at the time.

2. In a draft regulating apparatus, in combination, a T joint having a tubular body, adapted

for insertion into a smoke pipe as a part thereof, and a lateral pipe section the opening therethrough communicating with the interior of the body and the outside air, a manually adjustable damper in said body between the discharge end thereof and said lateral pipe section, a vane in said opening operable by differences in pressure at opposite sides thereof, and supporting means for said vane adjustable circumferentially in the plane of the axis of said vane, of means carried by said supporting means for designating different draft pressures, and means actuated by said vane for indicating on said pressure designating means the draft pressure in said smoke pipe at the time.

3. In a draft regulating apparatus, in combination, a T joint having a tubular body, adapted for insertion into a smoke pipe as a part thereof, and a lateral pipe section the opening therethrough communicating with the interior of the body and the outside air, a manually adjustable damper in said body between the discharge end thereof and said lateral pipe section, a vane in said opening operable by differences in pressure at opposite sides thereof, and supporting means for said vane adjustable circumferentially in the plane of the axis of the vane, of means carried by said supporting means for designating different draft pressures, and means on said vane for indicating on said pressure designating means the draft pressure in the smoke pipe at the time.

4. In a draft regulating apparatus, in combination, a T joint having a tubular body adapted for insertion into a smoke pipe as a part thereof and a lateral pipe section the opening therethrough communicating with the interior of said body and the outside air, a manually adjustable damper in said body between the discharge end thereof and said pipe section, a ring circumferentially adjustable on said pipe section, a vane pivoted in and to said ring on an axis transverse thereto operable by difference in draft pressure at opposite sides thereof, a dial plate attached to and adjustable with said ring and extending therefrom in longitudinal alignment with said opening and having means designating different draft pressures, and means on said vane at the periphery thereof for indicating on said designating means the draft pressure in the smoke pipe at the time.

5. The combination with a furnace draft flue having an air relief opening, a damper supporting frame mounted at said opening, a draft responsive damper pivotally mounted within said frame, a dial plate calibrated in terms of draft attached to said frame and extending into said opening, an indicator carried by said damper and cooperating with said dial plate to indicate the draft, a manually adjustable damper mounted within said flue between said air relief opening and the discharge end of said flue, said manually adjustable damper being adjustable until said indicator registers with the desired draft calibration upon said dial plate, said draft responsive damper then operating to maintain said draft.

RICHARD A. WALKER.
